SPRINKLER BEARING CONSTRUCTION

Harry D. Jacoby, Palos Verdes Estates, Calif., assignor to Walter V. Storm, Rolling Hills, Calif.

Filed Feb. 3, 1958, Ser. No. 713,051

2 Claims. (Cl. 239—264)

This invention relates to a sprinkler and is more particularly concerned with an overhead rotary sprinkler having a novel bearing construction.

The ordinary overhead rotary sprinkler involves an elongate vertically disposed bearing housing applicable to a water supply pipe, an elongate vertically disposed tubular spindle extending through and rotatably carried by the housing and a water distributing head carried by the spindle at the upper end thereof. The head is provided with a laterally and upwardly projecting water conducting arm or branch having a nozzle at its outer end adapted to direct a jet of water away from the head.

The ordinary sprinkler of the character referred to further includes a suitable drive means for rotating the head and the spindle relative to the bearing housing which means generally involves a spring loaded driver carried by the head and having an arm with a deflector at one end adapted to be acted upon by the jet of water issuing from the nozzle of the sprinkler.

Due to the reaction of the jet of water issuing from the nozzle and from one side of the distributing head, the spindle of the ordinary sprinkler is urged out of alignment in the bearing housing, with the result that the spindle only establishes point contact with the bearing housing at opposite ends thereof and at diametrically opposite sides thereof. As a result of this point contact, the bearing housing and/or spindle rapidly become worn to a degree that the spindle binds in the housing and the overall sprinkler construction is rendered ineffective.

An object of the present invention is to provide a novel sprinkler bearing which establishes uniform bearing engagement when the spindle is urged out of alignment with the bearing housing by the reaction of the jet of water issuing laterally from the distributing head.

A feature of the present invention is to provide a sprinkler bearing construction of the character referred to wherein the bearing housing and/or the spindle is provided with longitudinally spaced conical bearing surfaces, which surfaces establish flat bearing engagement with the portions of the constructions which they oppose when the sprinkler is in operation and when the bearing housing and spindle are urged out of alignment with each other as a result of the reaction of the jet of water issuing from the distributing head.

Another object of the invention is to provide a structure of the character referred to which is both easy and economical of manufacture and which is both highly effective and dependable in operation.

The various objects and features of my invention will be fully understood from the following detailed description of a typical preferred form and application of my invention, throughout which description reference is made to the accompanying drawings, in which:

Fig. 1 is a side elevational view of the sprinkler provided by the present invention and having portions thereof broken away to show the novel bearing construction that I provide in section.

2

Fig. 2 is an enlarged detailed sectional view of a portion of the construction illustrated in Fig. 1 and showing the relationship of the spindle and the bearing housings when the construction is not in use.

5 Fig. 3 is an enlarged broken sectional view showing portions of the construction illustrated in Fig. 2 and illustrating the manner in which the spindle bears in the bearing housing when the construction is in use.

10 Fig. 4 is a view similar to Fig. 2 and showing another form of the invention.

Fig. 5 is a view similar to Fig. 3 and illustrating the manner in which the spindle, in the form of the invention illustrated in Fig. 4 of the drawings, cooperates with the bearing sleeve when the construction is in operation.

15 The sprinkler construction provided by the present invention is applicable to the upper terminal end of a vertically disposed water conducting stand pipe P, or the like, and is shown as involving generally, an elongate vertically disposed bearing housing A fixed to and projecting upwardly from the pipe P, an elongate vertically disposed tubular spindle B extending through and rotatably carried by the bearing housing, a water distributing head C carried by the spindle at the upper end thereof, and drive means D adapted to rotate the head and the spindle relative to the bearing housing.

20 The sprinkler construction is shown as further including, sealing means E at the lower end of the housing A establishing bearing sealing engagement with the spindle B and the housing, and an upper sealing means F at the upper end of the housing A and establishing bearing sealing engagement with the head C.

25 The pipe P is shown as an elongate vertically disposed tubular element 10 that is internally threaded at its upper end 11, and is adapted to conduct and deliver water under pressure to be handled by sprinkler.

30 The bearing housing A that I provide is an elongate vertically disposed element having a straight, central longitudinal bore 12 extending therethrough, an externally threaded lower portion 13 threadedly engaged in the upper end of the pipe, an enlarged central portion 14 provided with suitable tool engaging flats 15 and an upper portion 16 of reduced diameter projecting upwardly from the top of the central portion. The central portion 14 of the housing A has a flat top or upper end from which the upper portion 16 projects or continues and which establishes an annular upwardly facing shoulder 17, which shoulder cooperates with an element of the sealing means F in a manner that will hereinafter be described.

35 The spindle B is an elongate vertically disposed tubular member with a central longitudinal flow passage 20 extending therethrough, an elongate central portion 21 having a cylindrical exterior surface, an enlarged flange-like lower portion 22 projecting radially outwardly from the lower end of the central portion and defining an upwardly facing annular shoulder 23, and an externally threaded upper portion 24 continuing upwardly from said central portion. The central portion 21 of the spindle is slightly longer than the bearing housing A and is engaged in the bore 12 of the housing A with working clearance and so that the shoulder 23 on the lower end portion of the spindle is spaced from and opposes the lower end of the spindle and so that the threaded upper end portion 24 of the spindle projects beyond the upper terminal end of the housing where it engages the head C as will hereinafter be described.

40 It will be apparent from the above, that the tubular spindle B projects through the bearing housing A, establishes open communication between the pipe P and the distributing head C.

45 The distributing head C in the form of the invention illustrated is an L-shaped member formed as by casting

and includes an elongate vertically disposed base 30 and an arm or branch 31 projecting laterally and upwardly from one side of the base.

The distributing head C further includes a waterway 32 communicating with the flow passage 20 in the spindle and extending through the branch 31 of the head. The branch 31 of the head is provided with a nozzle 33 at its outer end and communicating with the waterway 32 extending therethrough and is adapted to deliver a jet of water laterally and upwardly from the head.

In addition to the above, the head C is provided at its lower end with an enlarged bore 34 adapted to freely receive the upper terminal end of the bearing housing A and an internally threaded counterbore 35 continuing upwardly from the bore 34 and adapted to cooperatively engage and receive the upper threaded portion 24 of the spindle B and to secure the head and the spindle in fixed relationship to each other.

With the above relationship of parts, it will be apparent that when the upper end 24 of the spindle B is threadedly engaged in the counterbore 35 in the head C, the spindle and the head are rotatably coupled to the bearing housing A, the bearing housing A being engaged around the central portion 21 of the spindle and between the shoulder 23 at the lower end of the spindle and the bottom of the bore 34 in the head C.

The drive means D adapted to rotate the head and the spindle relative to the bearing housing A is shown as including an elongate vertically disposed pin 40 fixed to and projecting upwardly from the base 30 of the head C, in axial alignment therewith, a driver 41 rotatably carried by the pin, a bumper 42 fixed to and carried by the head to occur adjacent the outer end portion of the branch 31 of the head and adapted to be engaged by the driver, torsion spring means 43 between the driver and the pin and normally yielding urging the driver towards the bumper, and a deflector 44 on the driver adapted to be engaged by the jet of water issuing from the nozzle 33 to be deflected thereby and away from the bumper and against the resistance of the spring means.

With the above relationship of parts, it will be apparent that after the driver has been rotated or urged away from the bumper by the reaction of the jet of water on the deflector, it is urged back by the spring means so that it strikes the bumper, causing the head to rotate a short distance relative to the housing A.

Since the details of construction of the drive means D can vary widely in form and construction and do not effect the novelty of the present invention, I will not burden this specification with further detailed description of the said drive means.

The sealing means E at the lower end of the housing A is adapted to allow for free relative rotation and axial shifting between the spindle and the housing and to restrict the flow of water between the spindle and the housing.

The means E is shown as including a resilient rubber-like washer 50 engaged around the central portion 21 of the spindle to occur at the lower end thereof and seated on the upwardly facing shoulder 23 established by the enlarged lower end portion 22 of the spindle, and a bearing insert 51 engaged in an annular radially and downwardly opening recess 52 in the lower terminal end of the housing A.

The washer 50 of the means is of substantial thickness or vertical extent and is formed of a resilient rubber-like material, while the bearing insert 51 is formed of a plastic material such as polytetrafluoroethylene, commonly referred to as Teflon, or any other suitable material having a low coefficient of friction with the rubber-like matting washer 50.

With the means E set forth above, it will be apparent that the resilient washer 50 normally yieldingly presses against and establishes sealing engagement with the bearing insert 51. It will be further apparent that when the

spindle B and the bearing housing A becomes misaligned, as by the reaction of the water issuing from the nozzle 33, the resilient washer will not be shifted out of sealing engagement with the bearing insert, but will compensate for such misalignment and will maintain bearing sealing engagement about the entire circumference of the bearing insert.

The sealing means F at the upper end of the housing A is shown as including an annular bearing insert 60 engaged in an annular radially inwardly and downwardly disposed recess 61 in the lower end of the base 30 of the head C and freely passing the upper section 16 of the housing which enters the bore 34 in the head. A spring hood 62 is slidably engaged around the upper portion 16 of the housing and a compression spring 63 is provided between the spring hood 62 and the upwardly facing shoulder 17 on the central portion 14 of the housing and normally yieldingly urges the hood 62 upwardly and into sealing engagement with the bearing insert 60.

The spring 63 acts through the hood 62 and the insert 60 to normally yieldingly urge the head C and the spindle B upwardly relative to the housing A and thereby maintain the sealing means E at the lower end of the spindle and the housing in proper working engagement at all times.

In the form of the invention illustrated in Figs. 1 and 3 of the drawings, the bore 12 extending through the housing A is a simple straight unobstructed bore, while the central portion 21 of the spindle B is provided with an upwardly convergent bearing surface 71 at its upper end portion and a downwardly convergent bearing surface 72 at its lower end portion. The upper and lower convergent or conical bearing surfaces 71 and 72 on the spindle occur in the upper and lower end portions in the bore 12 of the housing A and are adapted to establish flat bearing engagement with the bore 12 when the construction is in operation and the spindle is urged out of alignment with the housing by the reaction of the jet of water issuing from the distributing head C thereof, and as clearly illustrated in Fig. 3 of the drawings.

In practice, the angle of the conical bearing surfaces 71 and 72 and their longitudinal extent can vary widely and is controlled and/or determined by the length of the central portion of the spindle B, the working clearance which is provided between the spindle and the bore of the housing and the amount of bearing contact desired. The shorter the spindle and the more working clearance that is provided between the spindle and the bore in the housing, the more acute the angle of the bearing surfaces 71 and 72 and the resulting amount of bearing contact which is maintained between the said surfaces and the bore in the housing is determined by the work load the bearing surfaces will normally be subjected to. This work load is determined by the particular design of the sprinkler and the water pressure under which it is designed to operate.

In the particular case illustrated, the portion of the spindle occurring between the bearing surfaces 71 and 72 is turned down or relieved as at 73.

In the form of the invention illustrated in Figs. 4 and 5 of the drawings, the spindle B' has straight longitudinally disposed upper and lower bearing surfaces 71' and 72' and the bore 12' in the bearing housing A' is provided with an upwardly divergent or conical bearing surface 74 to cooperatively engage the upper bearing surface 71' on the spindle and a downwardly divergent bearing surface 75 to cooperatively engage the lower bearing surface 71' of the spindle, when the construction is in operation and the spindle is urged out of axial alignment with the housing by the reaction of the jet of water issuing from the distributing head C'.

It will be apparent that the form of the invention now under consideration is substantially the same as that first discussed form, except that the conical bearing surfaces

74 and 75 are provided in the bore 12' of the bearing housing A' rather than on the spindle B'.

In the second form of the invention, the angle and the longitudinal extent of the bearing surfaces 74 and 75 can vary and are controlled and/or determined by the same factors set forth above in discussing the first form of the invention.

Throughout the drawings and to better illustrate the principle of the invention, the angle of the bearing surfaces 71-72 and 74-75 have been greatly exaggerated and should not be considered to be working drawings. In practice, a sprinkler embodying the present invention and having a housing with bore 2.0 inches long, .650 inch in diameter, and receiving its related bearing spring to have .005 minimum working clearance, the angle of the conical bearing surfaces would be 0°.

In practice, the bearing surfaces 71-72 and/or 74-75 on the spindle and in the bearing housing can be established by suitable machining operations formed or established by molding or casting when the spindle and/or bearing housings are established or can, if desired, be in the form of separate sleeves and/or inserts suitably applied or engaged in the construction.

Having described only typical preferred forms and applications of my invention, I do not wish to be limited or restricted to the specific details herein set forth, but wish to reserve to myself any variations or modifications that may appear to those skilled in the art and fall within the scope of the following claims.

Having described by invention, I claim:

1. In a sprinkler bearing construction involving an elongate vertically disposed bearing housing, an elongate tubular spindle freely engaged through and rotatably carried by the housing and a water distributing head fixed to the spindle having a nozzle inclined relative to the longitudinal axis of the spindle and adapted to direct a stream of water laterally relative to the longitudinal axis of the housing and the spindle including, longitudinally spaced oppositely disposed conical bearing surfaces on

the spindle and adapted to establish flat bearing engagement in the housing when the spindle is urged out of axial alignment with the housing, by the reaction of the jet of water issuing from the nozzle in the distributing head and resilient sealing means between the spindle and the lower end of the housing.

2. In a sprinkler bearing construction, an elongate vertically disposed bearing housing with a straight central longitudinal bore, an elongate tubular spindle freely engaged through the bore and rotatably carried by the housing and a water distributing head fixed to one end of the spindle having a nozzle inclined relative to the longitudinal axis of the spindle and adapted to direct a stream of water laterally relative to the longitudinal axis 15 of the housing and the spindle, said spindle having longitudinally spaced oppositely disposed conical bearing surfaces and adapted to establish flat bearing engagement with the bore in the housing when the spindle is urged out of axial alignment with the housing by the reaction of the jet of water issuing from the nozzle in the distributing head, said housing having a downwardly disposed sealing face at its lower end, said spindle having an upwardly disposed shoulder at its lower end opposing the sealing face, a resilient sealing ring between the sealing 20 face and shoulder, and spring means between the housing and the head normally yieldingly urging the spindle upwardly in the housing.
